FINGERNAIL DRYING DEVICE

Filed Oct. 2, 1940

Inventor

William Kisling

UNITED STATES PATENT OFFICE

123,781

DESIGN FOR A FINGERNAIL DRYING DEVICE

William L. Kisling, St. Louis, Mo.

Application October 2, 1940, Serial No. 95,573

Term of patent 7 years

To all whom it may concern:

Be it known that I, William L. Kisling, a citizen of the United States, residing at St. Louis, in the State of Missouri, have invented a new, original, and ornamental Design for Fingernail Drying Devices, of which the following is a specification, reference being had to the accompanying drawing, forming part thereof.

Figure 1 is a front elevational view of a fingernail drying device, showing my new design.

Figure 2 is a plan view.

Figure 3 is an end view.

I claim:

The ornamental design for a fingernail drying device, as shown.

WILLIAM L. KISLING.
